US00D898317S

(12) **United States Design Patent** (10) **Patent No.:** **US D898,317 S**
Hilmerson (45) **Date of Patent:** **** Oct. 6, 2020**

(54) **GUARDRAIL CART ASSEMBLY**

(71) Applicant: **Debra Lee Hilmerson**, Savage, MN (US)

5,018,629 A 5/1991 Lamar
5,713,584 A 2/1998 Crane
6,109,390 A 8/2000 Giannopoulos
(Continued)

(72) Inventor: **Debra Lee Hilmerson**, Savage, MN (US)

(**) Term: **15 Years**

(21) Appl. No.: **29/732,387**

(22) Filed: **Apr. 23, 2020**

Related U.S. Application Data

(63) Continuation-in-part of application No. 16/024,418, filed on Jun. 29, 2018, now abandoned, and a continuation of application No. 16/828,904, filed on Mar. 24, 2020, which is a continuation of application No. 16/529,621, filed on Aug. 1, 2019, now Pat. No. 10,597,057, which is a continuation of application No. 16/024,418, filed on Jun. 29, 2018, now abandoned, which is a continuation-in-part of application No. 29/640,861, filed on Mar. 16, 2018.

(57) **CLAIM**

The ornamental design for a guardrail cart assembly, as shown and described.

DESCRIPTION

A portion of this document contains material subject to copyright protection. The copyright owner has no objection to the facsimile reproduction by anyone of the patent document or the patent disclosure, as it appears in the Patent and Trademark Office patent files or records, but otherwise reserves all copyrights whatsoever. The following notice applies to this document: Copyright © 2020, Hilmerson Safety Services, Inc.

FIG. 1 is a perspective view of a rail cart assembly incorporating the claimed design.

FIG. 2 is front view thereof.

FIG. 3 is back view thereof.

FIG. 4 is a left side view thereof.

FIG. 5 is a right side view thereof.

FIG. 6 is top view thereof; and,

FIG. 7 is a bottom view thereof.

The broken lines in the drawings show portions of the guardrail cart assembly, which form no part of the claimed design.

1 Claim, 7 Drawing Sheets
